[57] CLAIM

The ornamental design for a cover for an electronic and/or optical equipment enclosure, as shown and described

DESCRIPTION

FIG. 1 is a front view of a cover for an electronic equipment enclosure in accordance with the design;

FIG. 2 is a side view thereof;

FIG. 3 is a top view thereof; and,

FIG. 4 is a perspective view thereof.

The broken line shown throughout the drawing figures is included for the purpose of illustrating environmental elements only and forms no part of the claimed design.

The rear of the article as well as any portions not shown behind broken line matter are not considered to be part of my claimed design.
